CLAIM

The ornamental design for display screen with graphical user interface, as shown and described.

DESCRIPTION

FIG. 1 is a front view of the display screen with graphical user interface showing a first embodiment of the design.

FIG. 2 is a second embodiment thereof.

FIG. 3 is a third embodiment thereof.

FIG. 4 is a fourth embodiment thereof; and,

FIG. 5 is a fifth embodiment thereof.

The broken lines shown in the Figures form no part of the claimed design. The broken line with long line segments separated by short line segments represents an outer edge of the display screen. The remaining broken lines represent portions of the graphical user interface.
